UNITED STATES PATENT OFFICE.

THOMAS P. ARCHER AND FRANK M. EDGAR, OF DETROIT, MICHIGAN, ASSIGNORS TO TERNSTEDT MANUFACTURING COMPANY, OF DETROIT, MICHIGAN, A CORPORATION OF MICHIGAN.

REVERSIBLE LATCH CONTROL.

Application filed July 29, 1925. Serial No. 46,829.

This invention relates to a remote control latch, and has for its object the provision of a control and pull to unit which is reversible so as to permit of a right or left hand assembly in an automobile body.

The reversible means incorporated in the control unit is very quickly assembled therewith in either a right or left hand position, thereby materially speeding up the production in automobile body assembly.

In the drawings:

Fig. 1 is an elevational view of a remote control for an ordinary door latch.

Fig. 2 is an elevation of the control unit showing the same reversed.

Fig. 3 is a plan view of the control unit disassembled from the automobile body.

Fig. 4 is a vertical section on the line 4—4 of Fig. 1.

In an automobile door there is contained the usual automobile door latch which includes a front plate *a* which slidably supports the latch bolt *b*, yieldingly pressed outwardly by the spiral spring *c*. There is also supported by the front plate the usual roll back *d*. The latch bolt *b* is provided with the beaded lug *f*, which may be engaged by the draft member *g*. This draft member *g* is provided with an elongated slot *h* at one end which may be slipped over the head of the lug *f* and then twisted around to engage under the head of the lug. This means of attaching the draft member to the bolt is described in the application of

Heintz and Archer, Ser. No. 15,174, filed March 13, 1925. This connection permits the spring *c* to take up any lost motion between the draft member and the latch bolt.

At a remote point from the locking unit is located a control unit which includes a plate *i*, having secured thereto the housing *j*. This housing is substantially U shaped in cross section and is secured to the plate *i* in spaced relation therewith. The housing and plate are provided with the bearings *k* and *m* respectively for rotatably supporting the stud *n*. A handle *o* is secured to one end of the stud and the actuator arm *p* is secured to an intermediate portion of said stud within the housing and projects up through the housing, the upper end of which is provided with a stud *q* having an enlarged head *r*. The draft member *g* is provided with the

elongated slot *s* at the end opposite the slot *h*, and this slot is adapted to be fitted over the head *r* and twisted through a small arc to lock the draft member to the stud *q* by engaging the same under the head *r*. An anti-rattling spring *t* is interposed between the disc *u* and the actuator arm in order to prevent any rattling between the arm and the draft member. The stud *n* is projected through the housing and is slotted, as at *v*. A spring *w* is arranged to be detachably anchored in the slot *v*, the other end of said spring arranged to be anchored to the laterally projecting ear *x* by simply hooking the spring over the edge of the ear.

Fig. 1 shows the assembly of this spring *w*, which exerts a pressure on the actuator arm *b*, tending to throw the same to the right, or a clock-wise direction. In Fig. 2 the spring is reversed and the spring thus exerts a yielding pressure on the actuator arm in the opposite direction.

This spring is very easily detached from engagement with the stud *n* and ear *x* for the purpose of reversing its position by slipping it out of the slot *v* and turning it over 180°. This converts the control unit into either a right or left hand unit, which permits the use of the control unit either on the right or left hand side of the automobile body.

The use of such a detachable and reversible spring permits the manufacture of a control unit which may be used either as a right or left hand unit by merely reversing the position of the spring. The pull-to and latch handle *o* may be placed in the stud *n* at any position by reason of the serrations *y* and the nut *z*.

The spring *w* forces the actuator arm over until the same strikes against the housing which serves as a stop, the spring holding the same there and preventing rattling of the arm against this stop. This also prevents any looseness in the spindle causing rattling. The slot *s* in the draft member *g* provides a lost motion connection between the draft member and the actuator arm, and permits the arm to move all of the way over if the latch bolt *b* should become stuck or should not enter all the way into the bolt socket. Obviously one of the slots, *s* or *h* could be omitted, but a more practical and

efficient mechanism may be had by using both slots.

What we claim is:

1. In a remote control latch for automobile doors of the class having a latch unit, a remotely positioned control unit and connections therebetween, a control unit provided with an actuating handle and a reversibly operable single acting actuator arm to permit of a right or left hand assembly of said control unit.
10
2. In a remote control latch for automobile doors of the type having a latch unit, a remotely positioned control unit and connections therebetween, a control unit provided with an operating handle, an actuator arm, and a spring for resisting movement of said handle in one direction, said spring being reversible to permit of a right or left hand assembly of said control unit.
15
3. In a remote control latch for automobile doors of the type having the latch unit, a remotely positioned control unit and connections therebetween, a control unit provided with an actuator arm and yielding means for resisting the movement of said actuator arm in one direction, said yielding means being reversible to permit the same to engage the actuator arm for resisting the movement of the actuator arm in the opposite direction to permit of a right or left hand assembly with said connections and latch unit.
25
4. In a remote control latch for automobile doors of the type having a latch unit, a control unit and connections therebetween, a control unit provided with an actuator arm and a spring for resisting the movement of said actuator arm in one direction, the said spring being reversibly mounted in said control unit to permit the spring to engage the actuator arm for resisting the movement of the actuator arm in the opposite direction to permit of a right or left hand assembly of
40
- 45
5. In a remote control latch for automobile doors of the type having a latch unit, a control unit in connection therebetween, a control unit including a plate, an actuator arm pivotally supported thereby, and yieldable and reversible means engaging the actuator arm for resisting the movement of the actuator arm in either one of two directions to permit of a right or left hand assembly of said control unit.
50
6. In a remote control latch of the type having the latch unit, a control unit, and connections therebetween, a control unit including a plate, an actuator arm pivotally supported on said plate, and a spring having one end detachably anchored to the actuator arm and the other end detachably anchored to the plate for resisting the movement of said actuator arm in one direction, said
60
- 65
7. In a remote control latch of the type having a latch unit, a control unit and connections therebetween, a control unit including a plate and housing secured thereto, a stud pivotally supported in said housing and projecting through the housing, an actuator arm carried by said stud, and a spring having one end detachably secured to said stud and the other end detachably anchored to said housing for resisting the movement of said actuator arm in one direction, said spring permitted to be reversed for resisting the movement of the actuator arm in the other direction to permit of a right or left hand assembly of said control unit.
75
8. In a remote control latch of the type having a latch unit, a control unit and connections therebetween, a control unit provided with an actuator arm and reversible means detachably secured thereto for yieldingly resisting the movement of said actuator arm in one direction, the said means when reversed resisting the movement of said actuator arm in the opposite direction which permits of a right and left hand assembly of said control unit.
80
9. In a remote control latch of the type having a latch unit, a control unit, and a draft member connecting the latch and control units, a draft member provided with a slot on one end to provide a lost motion connection between the latch and control units, said control unit including a plate and a housing provided with an opening, an actuator arm pivotally supported in said housing and projecting through the opening in said housing, and means for yieldingly resisting the movement of said actuator arm in one direction, the lost motion connection between the latch and the control units permitting said yielding means to normally hold said actuator arm up against one end of the opening in said housing to prevent rattling.
100
10. In a remote control latch of the type having a latch unit, a remote control unit and a draft member therebetween, a remote control unit including an actuator arm adapted to be connected to one end of the draft member, and an antirattling spring between said arm and draft member to prevent rattling when the draft member and actuator arm are connected together.
105
11. In a remote control latch of the type having a latch unit, a control unit and connections therebetween, a control unit provided with an actuator arm and spring means holding the actuator arm at the limit of its swing to prevent rattling thereof and of the spindle.
120
12. In a remote control latch of the type
130

having a latch unit, a remote control unit and a draft member for connecting the two units, a control unit comprising an actuator arm for connection to the draft member and a laterally acting antirattling spring between said arm and draft member, and a longitudinally acting spring means on said control unit for preventing rattling of said arm and its spindle.

In testimony whereof we have affixed our 10 signatures.

THOMAS P. ARCHER.
